UNITED STATES PATENT OFFICE.

KARL KROEHLING, OF NEW YORK, N. Y.

DOOR STOP.

Application filed September 16, 1926. Serial No. 135,745.

This invention relates to a door stop or device for maintaining a door in a predetermined open position. As is more or less common experience, doors often are slammed, closed, due to drafts or sudden gusts of wind or from other causes, and this often results in serious inconvenience and sometimes in more or less damage.

The object of the invention is the provision of a simply and inexpensively constructed device and at the same time one that may be readily applied to yieldingly maintain a door or other springing object in an open position so as to overcome the difficulty and inconvenience to which reference has been made. In carrying out the invention the stop made in accordance therewith is preferably constructed from a strip of metal or similar material so as to include angularly disposed legs adapted to engage respectively with a face of a door jamb and the adjacent edge portion of a door, together with a third leg or its equivalent for completing the article and causing the same to yieldingly maintain the door in an open position, and means by which the device may be maintained in place by association with a hinge or otherwise, as will be hereinafter more particularly described.

30 In the drawing Figure 1 is a perspective view illustrating the use of a door stop made in accordance with my invention.

Fig. 2 is a sectional plan on an enlarged scale.

35 Fig. 3 is an end elevation of the structure shown in Fig. 2.

Fig. 4 is a view similar to Fig. 2 showing another form of the invention.

Fig. 5 is a plan of the construction shown 40 in Fig. 4.

Fig. 6 is a view similar to Figs. 2 and 4 showing still another form of the invention, and

45 Fig. 7 is a front elevation of the door stop illustrated in Fig. 6.

In the drawing I have illustrated a part of a door jam as indicated at 10 and a door 11 connected thereto by hinges 12, one of which is indicated at 12. As illustrated in Figs. 1, 2 and 3 of the drawing the door stop may be made from a strip of suitable metal or similar material so as to include a circular or looped portion 13 having a leg 14 and also a leg 15 extending therefrom. These leg members are preferably at right angles to

each other. The leg 15 is provided with an extension which forms a third leg 16 of a triangular structure. The extremity of the leg 14 is preferably turned at right angles thereto as indicated at 17 and the leg 16 is 60 so placed that the free end 18 thereof bears against the outer face of the leg 14 adjacent the outturned end 17 thereof which acts as a stop for limiting the resiliency of the legs 14 and 15. In the use of this form of the 65 invention the loop 13 is so formed as to be adapted to fit over the head 19 of the pin by which the knuckles of one of the hinges are connected. In so applying the device when the door is opened to an approximate right 70 angle position the leg 14 is adapted to lie against a portion of the face of the door jam and the leg 15 to lie against a portion of the face or edge of the door 11 so as to yieldingly maintain the door in this position. It will be understood of course, that when it is desired to close the door the stop device must be removed.

In the form of the invention shown in Figs. 4 and 5 the stop is also made of a strip of suitable metal so as to be provided with a loop 20 adapted to fit a pin of a hinge 21. In this structure the angularly disposed leg members are indicated at 22 and 23. The leg 22 terminates in an extension 24, the extremity 25 of which is preferably bent at right angles thereto. Similarly the leg 23 terminates in an extension 26 the extremity of which is turned at right angles thereto as indicated at 27. The extensions 24 and 28 85 are in alignment so that the extremities 25 and 27 are substantially parallel to each other. These extremities 25 and 27 are provided with tapped openings to receive screw 90 threads pins 28 and 29 extending from a disk 30. The screw threads on the pins 28 and 29 are preferably right and left handed so that by turning the disk which is preferably knurled the extremities 25 and 27 may be moved toward or away from each other 95 to effect an adjustment of the stop. In this structure the loop 20 may be so formed as to replace one of the knuckles of the members of the hinge, in which instance as will be understood, it will be necessary to remove and 100 replace the pin of the hinge in setting the door stop in position.

In some instances it may be desirable to have the door stop permanently associated with the door jam. To provide such a struc- 110

ture I may employ a bracket 31 connected to the door jam by means of screws 32 or otherwise. One edge of the bracket 31 is provided with hinge knuckles 33 and 34 to form a part of a hinge. An intervening knuckle 35 of the hinge which may be secured in position by a suitable pin is formed at the extremity of an extension 36 of a lug 37 of the door stop. In this structure the other leg members of the door stop are designated at 38 and 39, the latter of which at its extremity as indicated at 40 is adapted to bear against the outer face of the leg 37 and the extension 36 forms a stop therefor in the same manner that the outturned end 17 of the leg 14 forms a stop for the leg 16 in the structure shown in Figs. 2 and 3. In the structure shown in Figs. 6 and 7, the leg 37 is adapted to bear against a portion of the face of the door jam and the leg 38 against a portion of the face or edge of a door to yieldingly maintain the same in an open position. When however, the use of the said device is not required or desired, the triangularly disposed leg members 37, 38, and 39 may be swung on the pivot or pin of the hinge to the position shown in dotted lines in the drawing in order as will be apparent to permit the door to be closed in the usual manner.

It will be understood that the forms of the invention as illustrated and described are more or less illustrative of the possibility of different forms and apparatus made in accordance with the invention may assume, as various other modifications may be employed without departing from the nature and spirit of the invention.

I claim as my invention:

40 1. A door stop comprising a strip of material having triangularly arranged legs two of which are adapted to bear respectively

against a door jam and the adjacent edge of a door associated therewith, and means for maintaining the stop in an operative 45 position.

2. A door stop comprising a strip of material having triangularly arranged legs two of which are adapted to bear respectively against a door jam and the adjacent edge of 50 a door associated therewith and a third leg adapted to bear at its extremity against one of the aforesaid legs and to yieldingly engage the same, and means for supporting the stop in an operative position. 55

3. A door stop comprising a strip of material having a loop adapted to engage the pin of a door hinge, angularly disposed legs extending from the loop and adapted respectively to engage a portion of a door jam 60 and a portion of the adjacent edge of a door associated therewith, and a third leg extending in an angular position from one of the aforesaid legs and adapted at its extremity to bear against the surface of the other aforesaid legs to yieldingly engage the same. 65

4. A door stop comprising a strip of metal having a loop adapted to engage the pin of a door hinge, a leg extending from the loop and having an angular extremity, a second 70 leg extending from the loop, the said legs being adapted respectively to bear against a portion of a door jam and a portion of the adjacent edge of a door associated therewith, and a third leg extending in an angular position from the second leg and adapted at 75 its extremity to bear yieldingly against the surface of the said first leg, the angular extension of which acts as a stop for the extremity of the said third leg. 80

Signed by me this 3rd day of September, 1926.

KARL KROEHLING.
